CAP FOR DRIVABLE FERTILIZER STICK

Jacob Douglas Gay, Jr., Fayette County, Ky.
(Pine Grove, Ky. 40470)

Filed July 6, 1973, Ser. No. 377,093

Term of patent 14 years

Int. Cl. D8—01, 99

U.S. Cl. D35—1

FIG. 1

FIG. 2

FIG. 3

FIG. 1 is a top plan view of a cap for drivable fertilizer stick embodying my design;

FIG. 2 is a front elevational view thereof;

FIG. 3 is an end view showing the left half of the cap in front elevation and the right half thereof in section, this view corresponding to one taken along line 3—3 of FIG. 1.

I claim:

The ornamental design for a cap for drivable fertilizer stick, as shown.
